(74) Attorney, Agent, or Firm — Johannes Kusters; 3M Innovative Properties Company

(57) **CLAIM**

The ornamental design for a respirator filter cartridge, as shown and described.

DESCRIPTION

FIG. 1 is a perspective view showing an embodiment of the new design for a respirator filter cartridge;

FIG. 2 is a front view thereof;

FIG. 3 is a rear view thereof;

FIG. 4 is a bottom view thereof;

FIG. 5 is a top view thereof;

FIG. 6 is a left side view thereof;

FIG. 7 is a right side view thereof;

FIG. 8 is a perspective view showing another embodiment of the new design for a respirator filter cartridge;

FIG. 9 is a front view thereof;

FIG. 10 is a rear view thereof;

FIG. 11 is a bottom view thereof;

FIG. 12 is a top view thereof;

FIG. 13 is a left side view thereof; and,

FIG. 14 is a right side view thereof.

In the drawings, the broken lines are for the purpose of illustrating portions of the respirator filter cartridge that forms no part of the claimed design.

1 Claim, 6 Drawing Sheets
